UNITED STATES PATENT OFFICE.

WILLIAM EARNEST GREER, OF ENOS, OKLAHOMA.

INCUBATOR.

Application filed November 27, 1922. Serial No. 603,586.

To all whom it may concern:

Be it known that I, WILLIAM E. GREER, a citizen of the United States, residing at Enos, in the county of Marshall and State of Oklahoma, have invented certain new and useful Improvements in Incubators, of which the following is a specification.

This invention relates to incubators.

The primary object of this invention is the provision of an incubator which is self-acting, requiring little attention in the details incidental to incubation.

A further and very important object of this invention is the provision of an incubator embodying means for automatic shifting and airing of eggs disposed therein for incubation, at required intervals.

Other objects and advantages of this invention will be apparent during the course of the following detailed description.

In the accompanying drawings, forming a part of this specification, and wherein similar reference characters designate a corresponding parts throughout the several views.

Figure 1 is a perspective view of the improved incubator.

Figure 2 is an interior plan view, partly in section, showing cooperating details of this invention.

Figure 3 is a cross sectional view, taken substantially on the line 3—3 of Figure 2.

Figure 4 is a cross sectional view, taken substantially on the line 4—4 of Figure 2.

Figure 5 is a transverse cross sectional view, taken through the improved incubator housing adjacent the floor thereof.

Figure 6 is a fragmentary cross sectional view, taken through the improved incubator, showing more particularly the cooperating details whereby it may be periodically aired.

Figure 7 is a transverse cross sectional view, taken substantially on the line 7—7 of Figure 6.

Figures 8 and 9 are fragmentary cross sectional views, showing steps incidental to egg shifting as automatically accomplished by the improved incubator.

In the drawings, wherein for the purpose of illustration is shown but the preferred embodiment of this invention, the letter A generally designates the improved incubator, which may include a housing B; egg supporting means C; heating means D; egg airing means E; egg shifting means F; and

means G for operation of the egg supporting means C.

The housing B is of any approved material, and preferably exteriorly constructed of wood, and interiorly lined with beaver board. The same includes side walls 10, 11, 12, and 13, a bottom 14, and detachable top 15. It is preferred to provide a closure member 16, as a part of the side wall 11, which includes a transparent pane 17 for visibility of the eggs and details within the compartment 20 of the housing C. An opening 25 is preferably provided in the top 15 of the housing B, having a closure lid or member 26 hinged adjacent said opening 25; this opening and its closure member, in fact, being a part of the egg airing means E to be subsequently described. Legs 28 may be provided, rigid with the bottom 14, for supporting the improved incubator housing B at a desired height.

Referring to the egg supporting means C, the same is of novel construction, and includes a shaft 30, which, at its lower end, is rotatably supported in an antifriction bearing 31 carried centrally of the bottom 14, the upper reduced end 31 of the shaft 30 preferably extending through a bearing 32 in the cover or cap 15 of the housing B. A flat circular disc 35 is rigidly affixed, as by a sleeve 36, to the shaft 30, just upwardly and in spaced relation with the floor 14 of housing B. This disc 35 may be of metal, and provided with relatively thin mesh wire screening 38 thereon; the disc 35 and its screening 38 having oval shaped openings 39 transversely therethrough arranged in series concentrically of the disc 35 for receiving the eggs 40 therein, substantially as is illustrated in Figures 2, 7, 8 and 9 of the drawings. The screening 38 may be covered by flannel or any approved material 41, and in this respect the screening and flannel 41 cooperate in receiving the eggs 40 against liability of breakage incident to shifting action, which will be subsequently described.

It is to be noted, that when the eggs 40 are disposed in their pockets or openings 39, the same extend upwardly and below the plane defined by the supporting disc 35.

Referring to the heating means D, the same is of novel arrangement, and very efficient in maintaining the compartment 20 of the housing B at the desired temperature,

normally 103° Fahrenheit. This heating arrangement contemplates the provision of a vertical casing 45 at the lower end of which a lamp 46 or analogous heating unit 5 is disposed, the heat from which arises upwardly through the compartment 47 of the casing 45. A hollow cylindrical shaped boiler 49 is preferably provided, rigid with the casing 45, and extending axially at right angles thereof; the boiler 49 providing an annular water receiving compartment 50, which may be provided with an approved filler opening and drain cock and having a passageway 51 longitudinally disposed there-through open at both ends and in communication with the compartment 47 of the casing 45, for receiving heat therefrom. A metal jacket 53 is preferably provided, outwardly of the boiler 49 and annularly encircling the same, having a closed end 55 adjacent the free end of the boiler 49 and in spaced relation therewith, whereby the heat waves emanating from the passage 51 of the boiler 49 will strike against said closed end 55 and be directed toward the casing 45, intermediate the interior surface of the jacket 53 and the outer surface of the boiler 49; the heat escaping at the open end 56 of the jacket 53 adjacent the casing 45, substantially as is illustrated in Figure 2 of the drawings.

The casing 45, boiler 49, and its jacket 53 are all mounted exteriorly of the housing B, preferably by bracket means 57, at the wall side 10. Piping 58 is preferably disposed within the incubator compartment 20, just below and in spaced relation with respect to the detachable top 15, which may be supported by brackets 59 as to encircle the compartment 20. The piping 58 at the juncture of the side walls 12 and 13, may be bent in U-shaped reduced diameter, as at 60, to avoid details of the egg airing means E to be subsequently described. Adjacent the housing wall 11, an inlet duct or conduit 61 is provided, which communicates the water compartment 50 of the boiler 49 with the passageway 63 of the heating tubing or piping 58. A partition 63' is provided between the inlet and outlet as shown in Figure 2. The operation of the heating fluid is thermosiphonic, and to this end the inlet conduit 61 is disposed relatively higher than the outlet conduit 64, so that the heated fluid of highest temperature may flow from the boiler compartment 50 into the tubing or piping 58 by way of the inlet 61, and in the direction indicated by the arrows in the drawings, completely flowing about the piping 58 and outwardly through the exit or outlet conduit 64 for return to the boiler

compartment 50 for reheating. In this manner, the heating fluid is maintained in motion for heating the incubator compartment 20, at a constant temperature, as above mentioned.

As a safety factor, in the maintaining of constant temperature within the incubator compartment 20, it is preferred to provide a closure or damper member 66 at the top of the heating casing 45, having a rod 67 fixedly connected thereto, said rod being pivoted as at 68 intermediate its ends to a bracket 69, which may be affixed to the jacket 53 at the free end thereof. A lever 70 is preferably oscillatively pivoted, as at 71, intermediate its ends, and being connected at one end thereof as by a link 72, to the free end of the pivoted arm 67. The other end of the lever 70 is preferably fixedly connected to the top of the thermostat 73 which is supported within the incubator compartment 20 by a bracket 74. Of course, the operating lever 70 has an end thereof extending into the compartment 20 to effect such construction.

The operation of the heating system, in so far as the thermostat 73 is concerned, is obvious, since should the temperature within the compartment rise above the desired temperature, normally 103°, expansion of the thermostat will rock the lever 70 so that the same will move the rod 67 upon its pivot 68, and lift the damper or closure 66 off of the heating casing 45. It is obvious that when the closure 66 is removed from the casing 45, the heat waves incident to the heating unit 46 will be dissipated exteriorly of the casing 45, and will not be directed through the heat jacket 53 as above outlined.

Referring to the egg airing means E, the same preferably comprises an auxiliary housing 75, which is disposed within the compartment 20 of the incubator A, including an upper section 76, which may be carried by the top 15 of the housing B; this section 76 defining a compartment or passageway 77 open therethrough and communicating with the opening 25 in the housing top 15. A section 78 of the auxiliary housing 75 is also carried by the incubator bottom 14, and has the compartment or passageway 79 therethrough communicating with the opening 80 provided in the incubator bottom 14. The passageways 77 and 79 are, of course, in alignment, and it can thus be seen that the auxiliary housing 75 provides a compartment which is open exteriorly of the incubator housing B, through the top opening 25 and bottom opening 80 in said incubator housing B. At the adjacent ends of the housing sections 76 and 78, they are provided with flexible guard pieces 81 and 82 respectively, which are of sufficient inherent rigidity to maintain a

proper position. Intermediate the facing edges of the guard portions 81 and 82, the disc 35 is disposed in intersecting relation with the passageway provided by the airing 5 housing 75. During rotational movement of the egg supporting disc 35 by means of the operating device G to be subsequently described, the eggs 40 will pass from the heated compartment 20 into the airing compartment 10 of the airing housing sections 76 and 78. Within these compartments, fresh air is continually circulating, so that the eggs 40 disposed therein will be aired. The flexible flannel portions 81 and 82 prevent excessive 15 escape of heat from the compartment 20, and yet are sufficiently flexible to permit passage of the eggs into the airing housing 75, by flexing of the same. To facilitate the flexing of the flannel portions 81 and 82 incident 20 to the eggs 40 brushing thereagainst, it is preferred to vertically split said flannel portions inwardly of their facing edges, substantially as is illustrated in Figure 4 of the drawings. It is apparent that in position 25 within the airing housing 75, as illustrated in Figure 7 of the drawings, the eggs 40 are aired from above and below in a thorough manner.

The egg shifting means F principally 30 comprises a U-shaped metal member 90, which may be attached as by flanges 91 to the inside surface of the housing floor 14; the same having an arcuate head portion 93 exteriorly faced with some yieldable material 94, as felt. This member 90 is disposed immediately below the disc 35, and during rotation of the latter, as will be subsequently described, the lower portions of the eggs 40 extending below said disc, through their 35 pockets or openings 39, will contact the facing material 94 and be slightly elevated from their disc, substantially as is illustrated in Figure 9 of the drawings, so that the eggs will be slightly shifted, by rolling action 40 on the arcuate top portion 93 as is evident.

Referring to the operating means G, the same may be any mechanism effecting a very slow movement, so that the disc 35 may be rotated through 360°, but once or twice every twenty-four hours. A convenient mechanism is that of providing a cable 96, wound spirally about the reduced end 31 of the shaft 30, and at its other end supporting a weight 97; said cable 96 being trained over a pulley 98 so that the weight may be suspended adjacent a side of the housing B. To retard action of the weight 97, a clock mechanism 99 may be provided, the key 50 end portion 100 of which may be affixed in the shaft end 31, so that as the clock runs down, the weight 97 is permitted to act in rotating of the shaft 30 for effecting the slow motion of the disc 35.

From the foregoing description of this

invention, it is apparent that an incubator has been provided, the egg supporting means of which is novel, and of such compact arrangement as to provide for the support of a large number of eggs on a relatively small 70 area. Since it is preferred that the disc make two revolutions every twenty-four hours, it is obvious that each egg will be aired within the airing housing 75 twice every twenty-four hours, and will likewise 75 be shifted by the means F twice every twenty-four hours. The disc 35 may, of course, be controlled by the operating means G to move through a greater or less number of revolutions in a predetermined time. The 80 normal period of incubation is twenty-four days, and the improved incubator details so cooperate, in automatic manner, as to only necessitate attention once every eight days. For the first week, it is preferred that the 85 door 26 be closed, and from the first week onward to the nineteenth day be opened to thoroughly air the compartment within the housing 75, and at which time the closure 26 is again disposed in shut relation. 90

Various changes in the shape, size and arrangement of parts, may be made to the form of invention herein shown and described, without departing from the spirit of the invention or the scope of the claims. 95

I claim:

1. An incubator comprising a housing having a heating chamber therein and an airing compartment communicating with said heating chamber, egg supporting means 100 rotatably mounted in said housing and having a portion positioned in said heating chamber and a portion in said airing compartment, and means for rotating the egg supporting means whereby the eggs may be 105 periodically moved through the airing compartment as the egg supporting means rotates.

2. An incubator comprising a housing having a heating chamber therein, rotary 110 egg supporting means, and means providing an airing compartment positioned in operative relation to a sector of said egg supporting means and through which said eggs will be moved on said rotary supporting means during rotation thereof.

3. An incubator comprising a housing, heating means for the interior of said housing, an airing casing open exteriorly of the housing, and egg supporting means movable through the chamber of said airing casing, the major portion of said egg supporting means being disposed within said heating chamber.

4. An incubator comprising a housing, means for heating the compartment of said housing, an airing conduit extending through said housing compartment, and rotating egg supporting means in the heating compartment having a portion thereof ex- 125 130

tending into the airing conduit for egg airing purposes.

5. An incubator comprising a housing having a heating compartment therein, means for heating said compartment, an airing conduit extending through said housing compartment, egg supporting means including a shaft, and a horizontally disposed disc affixed to said shaft for rotation therewith, said disc extending for its major portion thereof disposed for travel through said airing conduit.

6. An incubator comprising a housing, an egg supporting disk rotatable within the housing, means for heating said housing, egg airing means in operative relation to a sector of said disk, and operating means for rotating of said egg supporting means to cause eggs carried thereby to travel through said egg airing means.

7. An incubator comprising a housing providing a heating compartment therein, an airing housing carried within the heating compartment of said incubator housing and providing a compartment open exteriorly of the incubator housing, an egg supporting disc rotatably carried within the incubator housing having a portion thereof in movable intersecting relation with the airing compartment of said airing housing, and means for operating said egg supporting means for movement through the heating and airing compartments of said incubator.

8. An incubator comprising a housing, means providing a heating compartment within said housing, means providing an airing compartment within said housing, egg supporting means, and means for operating said egg supporting means for movement through said heating and airing compartments.

9. An incubator comprising a housing having a heating compartment therein, and including top, bottom, and side walls, a disc horizontally rotatable within the heating compartment of said housing intermediate

the top and bottom walls thereof, airing means including compartment sections carried by said top and bottom walls and opening outwardly therethrough, said sections terminating in spaced relation adjacent the upper and lower surfaces of said egg supporting disc, and means for rotating said disc so that eggs carried thereby will be periodically moved through the airing compartments of said sections.

10. An incubator comprising a housing, an egg supporting member rotatably mounted within said housing, and means mounted in said housing below said egg supporting member and adapted to engage the eggs and cause rotation of the eggs to adjust the positions thereof as the eggs pass over said means.

11. An incubator comprising a housing having a heating compartment, a disc rotatably disposed within said heating compartment having pockets therein whereby eggs disposed in said pockets will extend below said disc, and a member carried within said housing having an upper arcuate surface adapted for receiving the lower portions of said eggs thereagainst during movement of said disc, whereby the eggs may be rolled for shifting their positions.

12. An incubator comprising a housing having an incubating compartment therein, means for heating said incubating compartment at a constant temperature, egg supporting means rotatably disposed within said incubating compartment, means providing an airing compartment in said incubator and disposed in operative relation to a sector of the supporting means and adapted for periodically receiving eggs on said egg supporting means as the egg supporting means rotates, and means cooperating adjacent said egg supporting means for periodically shifting the position of eggs on said egg supporting means.

WILLIAM EARNEST GREER.
